**COOLANT-CIRCULATING ADJUSTABLE
GRINDING TOOL**

Arthur J. Holman, Brighton, N. Y.

Application November 13, 1951, Serial No. 255,914

9 Claims. (Cl. 51—207)

My invention relates to apparatus and methods for grinding curved surfaces on glass or other transparent materials and more especially to precision generator grinding of lens blanks in multiple by diamond milling over equatorial zones of a spherical carrier. The present device is an improvement over the mechanism described in copending patent application Serial No. 583,244, filed March 17, 1945, which issued as Patent No. 2,510,113 on June 6, 1950, entitled Method and Machine for Grinding Lenses, of which I am coinventor. The former apparatus does good grinding and serves well the purpose for which it was designed, namely, continuous production of finish ground surfaces on lens blanks which are attached, one by one, to the circular chuck holder before grinding and are removed therefrom, one at a time, after grinding while the chuck holder is being rotated continuously at suitable lens blank feeding rate. For polishing, these lens blanks must be remounted and, if they are polished singly, a very large number of spindles are required for volume production: if the ground blanks are mounted in multiple on chucks, great skill and accuracy are required to so mount them that the surface of each lens blank lies on a common spherical surface, otherwise there will be high, low and tipped surfaces and polishing time will be excessively long, particularly if the block is to be generator polished. If the block is polished on an ordinary spindle polisher, polishing time is still long and rejections rise seriously with inaccurate mounting of ground blanks.

The principal object of the present invention is to provide an equipment and a method of procedure to eliminate the necessity for remounting finish ground lens blanks for polishing. When this is accomplished successfully, the fine ground blanks can be polished very quickly and with great accuracy in a suitable polishing machine employing the generating principle, a machine wherein the relative movements of the lens blanks and the polishing elements produce true curvature on the work and maintain correct curvature of the polishing elements. The complete accomplishment of this principal object involves considerable invention including an improved lens blank carrier, an improved diamond milling generator adapted and arranged to handle the new lens blank carrier and a new generator polishing machine which will polish quickly all the fine ground lens blanks on the carriers as they come from the diamond milling generator. The present application covers the improved diamond milling generator and the improved lens blank carrier, also the methods by which they function. The new generator polishing machine is the subject of my copending patent application Serial No. 739,011, filed April 2, 1947, which issued as Patent No. 2,586,334 on February 19, 1952.

A second object of this invention is to compensate, at periodic intervals, for wear on the grinding rings, thereby limiting the amount by which any batch of ground blanks may depart from the specified grinding curve. It will be noted from examination of copending

patent application, Serial No. 583,244 hereinbefore referred to, also my copending patent application Serial No. 589,983, filed April 24, 1945, which issued as Patent No. 2,541,873 on February 13, 1951, for Lens Grinding Tool and Method, that, as abrading material is worn away, by continued grinding of lens blanks, the bore of the grinding rings will become enlarged. As a result, each successive lens blank is ground to a very slightly longer radius of curvature. With suitable diamond milling rings, it is expected that several hundred lens blanks can be ground for each one thousandth inch of wear on the grinding rings, nevertheless, when each diamond milling generator grinds several thousand lens blanks a day, the total wear on the grinding rings in a month's service will represent perhaps one sixteenth of a diopter difference in refracting power of the curved surface of the lens. Improved mounting of the grinding rings and a better ring structure permit adjustment of the bore of the grinding rings to limit, to any prescribed tolerance, the variation in curvature of surface ground on lens blanks.

Another object of this invention is to so form the grinding rings as to eliminate the necessity for spacer rings between the grinding rings progressively graded as to grit size and cutting speed, thereby simplifying the structures, eliminating loose parts, improving the distribution of coolant to the grinding areas, providing more effective scavenging of ground materials and eliminating completely all shoulder grinding; i. e., grinding of lens blanks against the edge of a grinding ring as distinguished from grinding of the blanks by the abrading material covering the cylindrical bore of the grinding rings. Elimination of shoulder grinding is important for several reasons: shoulder grinding invariably deforms the grinding tool, splinters the blanks, makes scavenging of ground material more difficult and decreases substantially the rate at which lens blanks may be fed to the grinding rings.

Another object of this invention relating to the generating of spherical surfaces, is to arrange the progressively graded grinding rings in such manner that lens blanks may be presented to the grinding rings from two directions for combining rough and fine grinding thereby permitting, (1) rotation of the carrier when fully loaded with lens blanks to be ground and, (2) complete grinding of all lens blanks on the carrier when the carrier has been rotated through an angle of 180 degrees.

A further object of this invention is to arrange the lens blanks on the surface of the carrier in such manner that the carrier may be brought to its proper grinding position, within the grinding rings, without grinding any lens blank down, at any point, to the depth of the ultimate finish ground surface.

Further objects are to increase the rigidity of the structures supporting the lens blank carrier so the carrier may be always precisely positioned within the grinding rings and may be so substantially supported as to permit rapid feeding of lens blanks to the grinding rings without causing chattering at the grinding surfaces; providing simple means for mounting the carrier in the supporting structures, feeding the carrier into grinding position, rotating the carrier to feed lens blanks to the grinding rings, withdrawing the carrier from grinding position and removing the carrier from its supporting structures.

Another object is to provide simple and effective means whereby toric surfaces may be generated in multiple on a suitable lens blank carrier and may be polished subsequently in multiple.

Still another object of the invention is to provide simple means whereby the carrier supporting and feeding structures may be easily and quickly swung out of operating position to permit free access to the grinding rings

for dressing, for adjustment to compensate for wear, or for replacement.

The ultimate object of this invention is development of the method for rapid production of lens blanks finish ground in multiple to a common spherical surface to specified curvature, said lens blanks being supported on a carrier suitable for insertion, subsequent to grinding, into a generator polishing machine wherein the fine ground spherical surface common to all lens blanks on the carrier may be polished quickly and accurately without departure from true spherical form.

This diamond milling generator is fully enclosed so the coolant most satisfactory for rapid cutting may be used without messing up either the operating personnel or the premises wherein the equipment is used. Coolant is fed to the grinding rings under pressure and is withdrawn from the generator, preferably, under partial vacuum to insure minimum leakage of coolant charged with ground material and maximum recovery of diamond grit loosened by grinding action. The machine is designed for large volume production and may be used for making precision optics but it will probably find its greatest use in the manufacture of ophthalmic lenses which are produced annually by the millions in this country. The device is not limited in design to any particular spherical or toric curvature, as suitable structures may be built to generate any curvature of lens surface from ten diopter to two diopter, or even beyond these limits, and each particular size carrier will accommodate from 100 to 150 per cent more lens blanks than can be ground successfully on checks in conventional lens lapping machines or in diamond milling machines employing cup type wheels. Moreover, since this device is a generating grinder, the yield of first quality product is better than 95 per cent whereas the current yield of first quality product with lens lapping machines is often as low as 40 per cent and seldom exceeds 55 per cent in plants where inspection is critical and a high standard is maintained. Each lens made in this device is ground with its optical center at the geometrical center of the blank, hence there will be no discarding of lenses which will not center out in edging. Because of this fact, blanks should be edged to finish size before being mounted on the lens blank carrier, thereby saving unnecessary grinding and polishing of lens surface which is eventually ground away in the edging process. It is expected that this diamond milling generator will effect a reduction of at least 50 per cent in cost of grinding ophthalmic lens blanks. Since the product of this generator is finish ground lens blanks so supported in multiple on a carrier that their ground faces lie on a common spherical surface, the carrier may be transferred to a generator polishing machine wherein polishing of all blanks on the carrier may be effected, in one operation, quickly and without distortion. Thus, this method of grinding is effective, not only in reducing grinding costs, but also in reducing the cost of subsequent polishing of the lenses.

Equatorial generator

It seems in order to point out the primary characteristic of this invention which distinguishes it from other diamond milling generators. During the recent war, many diamond milling generators were built which employed a cup type diamond milling tool. In these devices, any cup tool will grind any and all curvatures, within reason, on lens blanks depending on the angle formed between the axis of rotation of the tool and the axis of rotation of the lens blank in any particular set up of the generator. Essentially, these devices grind only the polar cap of a sphere: this polar cap may consist of one single lens blank or it may include multiple lens blanks carried on a shell but in no event is it possible to grind successfully surfaces approaching a hemisphere in extent, i. e., surfaces comprising 180 degrees

solid angle. In many respects, this polar cap grinding is similar to the grinding done in ordinary lens lapping machines which operate today, basically, after the fashion used for centuries in grinding lens surfaces. The distinguishing characteristic of my new diamond milling generator is the fact that its grinds surfaces on a sphere adjacent to the equator and does not grind at all on the polar caps because these areas are utilized for mechanical support of the polar axis whereon the sphere is rotated. Specifically, then, my improved diamond milling generator is an equatorial grinder whereas all other diamond milling generators, as well as all lens lapping machines, are polar cap grinders.

My device and the method of its operation may be best understood by reference to the drawings in which,

Fig. 1 is a plan view, at quarter scale, of the complete machine,

Fig. 2 is a front elevation, at quarter scale, of the complete machine,

Fig. 3 is an end elevation, at quarter scale, of the complete machine,

Fig. 15 is a sectional view, at half scale, on line 15—15 of Fig. 14 showing positioning of axis of carrier with respect to grinding rings for generating toric surface.

Referring now more specifically to the drawings in which like reference numerals indicate like parts, a base 1 (Figs. 1, 2, 3 and 4) of heavy cast metal is provided with two sets of integral machined bosses whereon are securely held and accurately aligned bearing brackets 2 and 3 each of which houses a precision cylindrical roller bearing as indicated at 4 (Fig. 4). A rotating tool unit, comprising hollow shaft 5 and tool supporting shell 6 suitably press fitted or shrunk together as shown within bearing 4, is journaled in bearing brackets 2 and 3, and a pulley 7 arranged for multiple V belt drive is suitably secured to shaft 5. Tool supporting shell 6 has an accurately machined cylindrical bore at its end of larger diameter wherein are snugly fitted, to prevent turning within the bore, multiple grinding rings comprising, from left to right (Figs. 4 and 7), rough grinding ring 8, fine grinding ring 9, and a second rough grinding ring 10 which is exactly like rough grinding ring 8 in composition and structure. A flanged retaining ring 11, secured to the end of tool supporting shell 6 by suitable screws, serves to retain the grinding rings in proper operating

position in the tool supporting shell. Grinding rings 8, 9 and 10, collectively, comprise the diamond milling tool. The tool supporting shell is enclosed in a split housing, lower portion 12 (Figs. 2 and 4) being secured by suitable bolts to machined pads on base 1 and upper portion 13 being secured to lower portion 12 by suitable bolts, all as shown in Fig. 2. A flanged ring 14, containing an accurate bore centered on the axis of rotation of tool supporting shell 6 and having an outer face square to said axis, is secured by suitable screws and a flanged fit to upper and lower portions 13 and 12 of the split housing.

Coolant circulation

Free circulation of coolant to the tool is supplied in the following manner: A bore 15 (Fig. 4) which runs the length of hollow shaft 5, carries coolant, supplied from a suitable source through a connection (not shown) with the outboard end of shaft 5, to the circular chamber 16 in the hub of tool supporting shell 6, circular chamber 16 being formed partly by the inner end of shaft 5, partly 15 by a plug 17 closing the bore in the hub of tool supporting shell 6, and partly by an annular recess turned in the hub of tool supporting shell 6. From circular chamber 16, coolant flows through a plurality of holes drilled in the body of tool supporting shell 6 all the way to the inner face of flanged retaining ring 11 which covers the ends of these drilled holes. In four axial positions under the grinding rings, saw cuts 18 (Figs. 4, 7 and 8) are made in the tool seating bore of tool supporting shell 6 into each drilled hole to a depth of half the diameter of the drilled hole. Rough grinding rings 8 and 10, composed of sintered powdered metal, are formed on their annular faces, as shown in Fig. 8, with curved recesses 19 extending each way from each drilled hole in tool supporting shell 6, and with radial semicircular depressions 20 (Fig. 10) which connect curved recesses 19 with the abrading surfaces of the rough grinding rings. Thus, after the multiple grinding rings have been inserted in the tool supporting shell 6, there are many passages for circulation of coolant distributed uniformly across the face and around the circumference of the abrading surface of the diamond milling tool. Coolant flowing to the right from the grinding tool (Fig. 4) will find its way over tool retaining ring 11 into the tool housing; coolant flowing to the left will pass into the housing through holes through tool supporting shell 6 as shown in the cross section at top of Fig. 4. All coolant will be withdrawn under partial vacuum from the tool housing through the opening in the bottom thereof.

Elimination of shoulder grinding

In cases where an unusually large amount of glass is to be removed from the surface of lens blanks or where fused bifocal flint blanks are to be ground as shown diagrammatically in Fig. 12, it is preferable to arrange the grinding rings as shown in Fig. 9, wherein fine grinding ring 9 has on either side a rough grinding ring 21 provided on each annular face with coolant circulation depressions as in Fig. 8, and each rough grinding ring 21 is, in turn, flanked with a rough grinding ring 22 provided with a beveled edge which is first to contact lens blanks as they are fed to the grinding tool. This arrangement of tool elements in the tool supporting shell can accommodate a grinding cut to the depth indicated as *b* (Fig. 9) without direct shoulder grinding whereas the tool arrangement shown in Fig. 7 can accommodate a grinding cut only to depth *c* before shoulder grinding begins. While on the subject of shoulder grinding, it is well to point out the advantages gained by molding coolant circulation channels in the rough grinding rings versus employing spacer rings to provide coolant circulation channels. It will be evident from examination of Figs. 8 and 10 that rough grinding rings are in contact with annular faces of the fine grinding ring at all areas around the circumference of the tool, except at areas

opposite semicircular depressions 20, hence there is no cylindrical zone on the face of the abrading tool where no grinding takes place. If spacer rings are employed between the grinding rings, then there will be a non-grinding cylindrical zone at the tool surface opposite each spacer ring and this will mean shoulder grinding against the annular faces of fine grinding ring 9. This condition would cause rapid wearing of the fine grinding ring, due to overloading, and would limit seriously the rate at which lens blanks can be fed to the grinding tool.

Grinding ring wear

From calculations based on data showing rate of wear of cup type diamond wheels, it is estimated conservatively that, in an equatorial diamond milling generator designed to generate "six curve" surface (i. e., cylindrical bore of grinding tool is $\frac{1}{6}$ meter), which is the machine illustrated in the drawings, about 600 lens blanks of 52 mm. diameter will be ground for each one thousandth inch radial wear on the grinding tool. Standard tolerance in ophthalmic lens production seems to be $\frac{1}{16}$ diopter. Such tolerance on a "six curve" generator means that the bore of the grinding tool may increase, due to wear in grinding, by .0677 inch in diameter before it need be readjusted, hence it is estimated that about 40,000 lens blanks may be ground before normal tool wear will exceed standard tolerances in lens surface refracting power. It is further estimated that the present equatorial grinding generator will grind about 200 lens blanks per hour, hence the bore of the grinding tool will not require adjusting to compensate for normal wear till the generator has operated 40,000/200 or approximately 200 hours or 25 eight hour shifts which is about once each month if the generator is operated eight hours a day.

In manufacturing diamond abrading wheels in which the sintered abrading material is bonded to steel or other solid metal supporting structure, it has been found difficult and uneconomical to make the diamond impregnated layer much less than $\frac{1}{10}$ inch in depth. In my improved grinding rings I propose to use sintered powdered metal throughout the entire ring, the diamond grit impregnation going to a depth of $\frac{1}{8}$ inch or less as shown by the broken line drawn across the grinding ring sections in Figs. 7 and 9, and by the circle drawn on the annular face of fine grinding ring 9 shown in Fig. 11. I also propose to make the grinding rings with a removable radial key section as shown in Fig. 8 at 60 and in Fig. 11 at 61. When wear on the grinding rings approaches the limit prescribed by tolerance in variation of lens surface curvature, the grinding rings are removed from the tool supporting shell 6, the radial key section is removed from each grinding ring and is replaced by a narrower radial key section the width of which, circumferentially, is just sufficient to restore the grinding ring to its original bore when the ring is sprung so both its ends make contact with the new and narrower radial key section. This operation will, of course, reduce the outside diameter of the grinding ring and suitable shim rings will be required around the grinding rings when they are reinserted in the cylindrical bore in tool supporting shell 6. A shim ring common to all grinding rings in the tool may be used if it is suitably perforated to permit free flow of coolant through the tool. Combined shim rings and radial key section sets may be made up in advance and stocked for use when required. Sintered powdered metal grinding rings are easily molded to provide coolant circulation channels as specified, the problem of bonding the diamond grit impregnated sintered powdered metal on steel or other metallic supporting rings is eliminated, and sintered powdered metal rings may be sprung easily in the manner hereinbefore described and without damage to the diamond impregnated layer. Thus, my improved grinding ring structures are particularly advantageous for use in my equatorial diamond milling generator.

Spherical carrier

A spherical lens blank carrier 23 (Figs. 4, 5 and 6), with polar caps removed, is provided with a plurality of recesses wherein lens blanks fit with slight clearance, each recess having a ring seat 24 of somewhat smaller diameter than the recess whereon the lens blank rests independently of its peripheral edge as shown in Fig. 13, each ring seat being square to and centered on a radius of the spherical surface of the carrier and positioned at the same radial distance from the center thereof. It is obviously advantageous to support molded lens blanks independently of their peripheral edges because, when lens blanks are so mounted, irregularities in molded peripheral edges cannot cause tilting of lens blanks on their seats. Fig. 5 shows the arrangement of lens blanks on the carrier as viewed in elevation. Fig. 6 shows the arrangement of lens blanks on the carrier as viewed in plan. Fig. 4 shows the internal structure of the carrier which comprises a lower section 25 and an upper section 26 between which sections is seated equatorial ring gear 27, the latter being prevented from rotating with respect to sections 25 and 26 by dowel pin 28 which passes through gear 27 and enters both sections of the carrier. A conical journal stud 29 provided with an integral notched ring suitable to be engaged by a socket wrench, is seated on the bottom of a recess in upper section 26 and fits snugly in an axial bore through upper section 26 and lower section 25, the lower end of conical journal stud 29, of somewhat smaller diameter, being threaded to fit accurately in the threaded bore of conical journal sleeve 30. The body of conical journal sleeve 30 is the same diameter as conical journal stud 29 and fits snugly in the axial bore through lower section 25 of the carrier; the head of conical journal sleeve 30 is the exact counterpart of the head of conical journal stud 29 and is seated on the bottom of a recess in the bottom of lower section 25. By using a pair of socket wrenches, conical journal sleeve 30 is screwed tightly on conical journal stud 29 thereby locking all parts of lens blank carrier 23 together and also providing a pair of accurately aligned and correctly spaced axial conical journals. Conical journal stud 29 and conical journal sleeve 30 are, preferably, hardened and ground all over. The body of lens blank carrier 23 may be made of Dow metal for lightness and strength and, in the larger sizes, the carrier may be made hollow.

It will be observed from examination of Figs. 5 and 6, that the lens blanks are not equally spaced around the carrier 23, but at one great polar circle the spacing between lens blanks is greater than at any other place on the surface of the carrier. Examination of diagrammatic Fig. 12 shows the reason for this planned irregularity in spacing of lens blanks. In Fig. 12 the rectangle represents the outlines of the cross section of the grinding tool with the line representing the grinding surface extended beyond each edge of the grinding tool. The right half of Fig. 12 shows a lens blank edge at a distance *d* from a great polar circle; the left half of Fig. 12 shows a lens blank edge at a distance *e* from the same great polar circle. The long arc tangent to the grinding surface of the tool represents the curvature to be ground on the lens blanks, the other arc representing, in each case, the surface of the unground blank. As the lens blank carrier is moved from right to left, along the axis of rotation of the tool to the position shown in Fig. 12, it is apparent that no part of the lens blank having its edge at distance *e* from the great polar circle would ever contact the grinding surface of the tool but the lens blank having its edge at distance *d* from the great polar circle has a portion of its surface which projects above the line of the grinding surface of the tool, hence that portion of the lens blank would be ground off as the carrier is fed along the axis of rotation of the tool. If the lens blank were mounted so that its edge was on the great polar circle, i. e., no spacing between lens blanks on the carrier, then that edge of the blank would be ground completely by the

rough grinding ring as the carrier is moved along the axis of rotation of the grinding tool and subsequent feeding of lens blanks to the grinding tool by rotation of the carrier would not effect any further grinding of this edge of the lens blank, even by the central fine grinding ring, thus a portion of the blank would not be fine ground and hence this lens blank would have to be rejected. It is quite apparent, therefore, that it is advantageous to provide extra wide space between lens blanks on the carrier at one great polar circle and, moreover, it is necessary to index the carrier to proper angular position when it is inserted in the cradle as hereinafter noted.

Cradle for spherical carrier

Lens blank carrier 23 is supported in a slidably mounted cradle (Figs. 1, 2, 3, 4 and 6) in the following manner: Cradle 31, substantially spherical in form, splits in two halves at the equator, lower half 32 and upper half 33 being hinged together by hinge pin 34 which fits accurately in bores in two aligned bosses 35 carried at the ends of brackets integral with upper half 33, and also in bores in four aligned bosses 36 carried on a bracket integral with lower half 32 of cradle 31. Also integral with lower half 32 of cradle 31 is a pair of long parallel bosses 37, each containing an accurate bore, the axis of which is parallel to that of the other bore and both axes lie in a plane parallel to the equatorial plane at which cradle 31 is split. A pair of parallel guide rods 38 is a free but accurate sliding fit in the bores in bosses 37 and serves to support slidably mounted cradle 31. While I have described cradle 31 as substantially spherical in form, it will be noted from Fig. 4 that lens blank carrier 23 is contained within cradle 31 and also that cradle 31 must slide through the grinding tool to such position that the polar axis of carrier 23 lies in the medial plane of the grinding tool. For these reasons, lower half 32 and upper half 33 of the cradle are flattened internally to provide suitable support for conical journal boxes 39 and 40, respectively, wherein lens blank carrier 23 is journaled, also, lower half and upper half 33 of the cradle have an external contour which is cylindrical in form over those areas which must be so formed to permit the cradle to slide into operating position within the grinding rings. A cylindrical surface 41 and a flanged seat 42 are continuous over lower half 32 and upper half 33 of the cradle and are, respectively, an accurate sliding fit in the bore and against the face of flanged ring 14 attached to the casing enclosing the tool supporting shell, and serve to square, align and center the cradle within the grinding tool and thus properly position and fixedly maintain the polar axis of the lens blank carrier as lens blanks are fed to the grinding tool by the rotation of said carrier. A pinion 43, meshing with equatorial gear 27 on lens blank carrier 23, is fixed on one end of shaft 44 which is journaled in a bore in lower half 32 of the cradle and carries fixedly mounted on its other end worm gear 45 (Fig. 4). A worm 46, carried on shaft 47 meshes with worm gear 45. Through this gear train, lens blank carrier 23 is rotated, by power supplied by a small motor (not shown), to feed lens blanks to the grinding tool at optimum cutting rate.

A pair of brackets 48, integral with base 1 (Figs. 1, 2 and 3), supports at their ends bosses 49 which are bored to fit snugly on hinge pin 50. A tilting bracket 51 is bored to fit snugly on hinge pin 50 and carries a pair of bosses 52 containing parallel bores wherein parallel guide rods 38 are a free sliding fit. The other ends of parallel guide rods 38 are secured in bores in bosses 53 (Fig. 1) which are integral with flanged ring 14 mounted on the housing enclosing the tool supporting shell. A control arm 54 is provided at one end with a boss bored to fit on hinge pin 34 and at the other end with a boss bored to fit on pin 55 by means of which it is connected with lever arm 56 to which power is supplied by suitable means (not shown) to slide cradle 31 containing lens blank carrier 23 from loading to grinding position and vice versa.

Operation of equatorial generator

Although I have not shown mechanism for so doing, the operation of my equatorial diamond milling generator can easily, and should, be made automatic except for loading the lens blank carrier in its cradle before grinding and taking it out after the lens blanks are ground. Power is supplied through multiple V belts to pulley 7 to rotate the grinding tool at optimum cutting speed. For loading, cradle 31 is slid on parallel guide rods 38 all the way to the right (Figs. 1, 2 and 6) by operation of lever arm 56 and upper half 33 of the cradle is swung open to the right as illustrated in Fig. 6. Lens blank carrier 23, fully loaded with lens blanks to be ground as shown in Fig. 5, is then dropped carefully into place in lower half 32 of the cradle and equatorial gear 27 is meshed with pinion 43 in indexed position. Upper half 33 of the cradle is then swung back into closed position and a snap ring 62 or threaded ring is placed over or screwed on the boss protruding from the left side of the cradle (Figs. 4 and 6) thereby locking the two halves of the cradle securely together and making the polar conical journals on the carrier fit accurately in the polar conical journal boxes in the cradle. It is to be noted here that conical type bearings will permit hinged opening and closing of the cradle, also this type of bearing is most satisfactory for aligning the axis, centralizing the carrier in the cradle and accommodating thrust loads. By operation of lever arm 56, loaded cradle 31 is slid to the left on parallel guide rods 38, cylindrical surface 41 on cradle 31 enters the bore in flanged ring 14, circulation of coolant commences and those portions of all lens blanks on the carrier which project beyond the cylindrical bore of the grinding tool will be ground away as the cradle continues travelling toward the left and is finally stopped when flanged seat 42 on the cradle makes complete contact with the outer face of flanged ring 14. The structures are such that the medial plane through the grinding tool now passes through the polar axis of the spherical carrier, i. e., the grinding tool encircles the spherical carrier about a polar great circle. The lens blank carrier is now in correct position for grinding the lens blanks carried thereon and power is applied to equatorial gear 27, through the means described, to rotate the carrier on its polar axis thereby feeding lens blanks to the grinding tool, the lens blanks on the carrier at positions to the left of the medial plane through the grinding tool will be fed to the grinding tool from one direction and the lens blanks on the carrier at positions to the right of the medial plane through the grinding tool will be fed to the grinding tool from the opposite direction. Thus, the forces applied to the grinding tool in the axial direction, by feeding of lens blanks to the tool, constitute a couple and are balanced. The forces applied to the carrier, through rotative grinding by the tool, constitute a steady balanced torque, which tends only to rotate the cradle, not to displace it from its centralized position. It appears therefore, that, in this equatorial method of grinding, there are no unbalanced forces tending to set up vibration, hence lens blanks can be ground at maximum feeding rates and the ground surfaces will be free from chatter markings.

If the apparatus has been accurately constructed and is maintained in good condition, one half revolution (180 degrees) of the carrier completes the rough and finish grinding of all lens blanks on the carrier, circulation of coolant is then stopped, the cradle is returned to its position at the extreme right on guide rods 38, the snap ring or threaded ring is removed from the projecting boss on the cradle, upper half 33 of the cradle is swung open and carrier 23 with its ground lens blanks is lifted out of the cradle and transferred to a cleansing bath, prior to being inserted in a cradle in a polishing generator. Thus, the grinding cycle is completed.

Toric surfaces

Interesting and thoroughly practical further applications

of my improved equatorial diamond milling generators and methods may be made in ophthalmic lens manufacturing plants for volume production of toric surfaces. For instance, a special "six curve" lens blank carrier 57 (Figs. 14 and 15) may be used in a "five curve" diamond milling generator to rough and fine grind, successively and simultaneously, "six-five curve" toric surfaces in multiple. A "six curve" lens blank carrier cradle provided with proper driving gear arrangement for rotating special carrier 57 would be required, also it would be necessary to have a properly off set supporting and feeding structure for the cradle so the carrier 57 would be brought into position with respect to "five curve" grinding rings as shown in Figs. 14 and 15. For this type of surface grinding, a rough grinding ring 58 provided with coolant circulation channels as in Figs. 8 and 10, would be required, also a fine grinding ring 59 which is one half the axial width of fine grinding ring 9 (Fig. 7) used for generating spherical surfaces. It will be noted from Fig. 15, that the polar axis of special carrier 57 lies in the plane of the left annular face of fine grinding ring 59 because it is the left edge of the abrading surface on the fine grinding ring which generates the final toric form on the surface of each lens blank as it passes thereunder. Subsequent polishing of the fine ground toric surfaces in multiple is described in my copending patent application for polishing generators previously referred to.

Adjusting grinding rings

Whenever it becomes necessary to get at the grinding rings, the screws (Figs. 3 and 4) retaining flanged ring 14 in position on the tool supporting shell housing are removed and flanged ring 14 (Figs. 1 and 2) is pushed to the right as far as it will go, the guide rods 38 will slide through bores in bosses 52 until bosses 36 on the cradle contact bosses 52 and then the entire cradle supporting structure may be swung to upright position and out of the way as tilting bracket 51 swings through 90 degrees on hinge pin 50. When work on the grinding rings is completed, the cradle supporting structure is swung back into horizontal position, flanged ring 14 is drawn all the way to the left and reseated on the tool supporting shell housing, retaining screws are inserted and screwed up tightly and the apparatus is again ready for grinding operations.

Lens blanks edged to final size

In ophthalmic lens manufacturing plants it has become standard practice to use lens blanks molded to 52 mm. diameter although first quality lenses are seldom, if ever, required to center out to more than 44 mm. diameter. However, even with this wide latitude of 4 mm. on a side, many finished lenses now fail to meet first quality requirements because they will not center out to 44 mm. diameter: this because blanks are tipped when mounted for second side grinding or because of excessive prismatic grinding of blanks mounted around the periphery of large grinding shells. It is of interest to note how much needless surfacing of glass can be eliminated when lens surfaces are generated on blanks in such manner that the geometrical center of the lens is also its optical center. Since the area of a circle is proportional to the square of its diameter, the ratio of areas of 44 mm. and 52 mm. diameter blanks is equal to $(44/52)^2$ or .717; so generator ground and polished lenses, if edged to finished diameter before surfacing, would save about 28 per cent of surface grinding and polishing. Moreover, lens blanks stuck together in sticks can be edged at much less cost than can finished lenses which must be edged singly. The use of edged blanks in my improved equatorial generator will represent further saving in cost of grinding rings and further reduction in grinding and subsequent polishing costs because an average of 25 per cent more lens blanks can be accommodated on a carrier. For example, on a "six curve" carrier, as shown in the drawings,

sixteen 52 mm. diameter blanks are accommodated whereas twenty 44 mm. diameter blanks can be equally well fitted on a "six curve" carrier. This would represent 25 per cent more salable product from each generator. Edged blanks would permit further economies in operation: edged blanks seat better in carrier recesses and with less clearance, thus further eliminating factors tending to produce inferior product.

In applying my improved equatorial diamond milling generator to lens manufacture, it is not necessary to have a special size machine for each curvature to be generated. For example, in making ophthalmic lenses from "four curve" to "ten curve," not more than six different machine sizes are desirable, intermediate lens curves being ground by using grinding rings of suitable bore in the next larger machine. For each desired curve to be generated, carriers are equipped to accommodate that curve but it will not be necessary to have a cradle size for each carrier size: in some sizes, a cradle may accommodate carriers varying in diameter up to a "half curve." As has been stated hereinbefore, toric surfaces of various cylindrical powers may be generated on any spherical curve generator by substituting suitable grinding rings and providing the machine with the proper carrier, cradle and off set support for the cradle. These special items of equipment represent but a small extra cost.

Prime advantages of equatorial generating method

Engineers skilled in the art of lens making will readily understand the principal advantages my improved equatorial diamond milling generator offers, most of which have been stated as objects of this invention. It is to be pointed out, however, that the greatest possible precision in lens grinding is to be had from this machine and for the very simple reason that there cannot possibly be any rolling off at the edges of the ground surface: this because the grinding is done all around the blanks mounted on the spherical carrier and by grinding rings of precision form which do not and cannot become deformed through service. Since there are ground lens blanks located at both ends of many diameters of the spherical carrier, it is a simple matter to measure curve diameter by micrometer and know precisely, to a thousandth of an inch or closer if desirable, just what curvature has been generated on the lens blanks on each and every carrier. These are prime advantages of the equatorial generating method and render it most valuable in the production of matched lenses such as are required on the revolving lens wheel in my Optical Rectifier as described in Letters Patent of the United States No. 1,957,457, dated May 8, 1934.

In the manufacture of the highest grade optical surfaces for photographic lenses and the like, it may be advantageous to rough grind the blanks in one equatorial generator and fine grind them in another: it might even be worth while to intermediate grind in a second generator before finish grinding in a third machine. Should this practice be followed in precision optics manufacture, it is obvious that only one grain size of diamond grit will be used in each grinding generator but multiple grinding rings will still be required and the functioning of the generator will be substantially the same as hereinbefore described. In other words, the equatorial generator will function equally well for any one particular fineness of grinding if the multiple grinding rings shown in Figs. 7 and 9 all contain the same diamond grain size.

The structures I have illustrated and described represent, for the present, the preferred forms of my device. It is to be understood, however, that other mechanisms might be designed and constructed by those skilled in the art, for performing the essential functions of the present structures, namely equatorial grinding of multiple lens blanks mounted on a spherical carrier. The attached claims are drawn sufficiently broad to cover any and all devices of this character, also the methods of their use,

and it is the intention that the claims be so interpreted.

Having thus fully described my improved equatorial diamond milling generator, also my multiple lens blank carrier and methods of operation to produce curved surfaces on multiple lens blanks mounted on a carrier, what I claim is:

1. In an equatorial generator, a rotating tool unit comprising a hollow shaft and a tool supporting shell securely attached thereto, a cylindrical bore in the end of said tool supporting shell, multiple coolant circulating channels through said tool supporting shell connecting with the coolant channel through said hollow shaft, multiple saw cuts in said cylindrical bore cut partly through said multiple coolant circulating channels, a plurality of grinding rings removably supported in said cylindrical bore and provided with coolant circulation channels connecting said multiple saw cuts with the abrading surfaces of said plurality of grinding rings, and a flange secured to the end of said tool supporting shell to retain said grinding rings in operating position and to cover ends of said multiple coolant circulating channels in said tool supporting shell.

2. In an equatorial generator, a rotating tool unit having a cylindrical bore fitted with a plurality of grinding rings of differing grit grain size, said grinding rings being arranged in such order that the centrally mounted grinding ring has the finest grit grain size, the two grinding rings flanking said central grinding ring are next coarser in grit grain size and the outer grinding rings are coarsest in grit grain size, said outer grinding rings having beveled edges to provide for extra deep cuts without shoulder grinding.

3. In an equatorial generator, a rotating tool unit having a cylindrical bore fitted with a plurality of grinding rings of differing grit grain size, said grinding rings being mounted in such order that grit grain size increases progressively in both directions from the middle along the axis of rotation of said rotating tool unit.

4. In a rotating tool unit adapted and arranged for coolant circulation, diamond grit impregnated sintered powdered metal grinding rings having internal cylindrical abrading surfaces and concentric external cylindrical seats and being mounted in multiple in a cylindrical recess in said rotating tool unit, alternate grinding rings being formed with radial and connecting transverse channels in their annular surfaces, through which channels coolant may flow to said cylindrical abrading surfaces when said grinding rings are mounted in said rotating tool unit.

5. In a rotating tool unit, an adjustable grinding ring comprising a diamond grit impregnated sintered powdered metal grinding ring having an internal abrading surface and a concentric external cylindrical seat suitable for mounting in a cylindrical recess in said rotating tool unit and being formed with a radial key opening wherein progressively thinner radial key sections may be substituted as required to compensate for increased diameter of bore, due to wear, a diamond grit impregnated radial key section, and a shim ring of such thickness that the radial ends of said grinding ring press firmly against the sides of said radial key section when said adjustable grinding ring is inserted in the cylindrical recess in said rotating tool unit.

6. In a rotating tool unit arranged for coolant circulation, a grinding ring adjustable to compensate for wear, comprising a diamond grit impregnated grinding ring having an internal abrading surface and a concentric external cylindrical seat suitable for mounting in multiple in a cylindrical recess in said rotating tool unit and being formed with a radial key opening wherein progressively thinner radial key sections may be substituted as needed to compensate for wear, said grinding ring being formed also with connecting radial and transverse channels in its annular faces through which coolant may flow to the abrading surfaces when grinding rings are mounted in multiple in said rotating tool unit, and a radial key section.

7. A coolant-circulating grinding tool for combined

13

rough and fine grinding, comprising a fine grinding ring and a rough grinding ring, each provided with cylindrical abrading surfaces mounted on a common axis with an annular face of said fine grinding ring in contact with an annular face of said rough grinding ring, the contacting face of said rough grinding ring being formed with connecting lateral and radial channels therein through which coolant may flow to the abrading surfaces of said grinding rings.

8. A coolant-circulating grinding tool for combined rough and fine grinding, comprising a fine grinding ring and a pair of rough grinding rings, each provided with cylindrical abrading surfaces, mounted on a common axis in such manner that an annular face of each rough grinding ring is in contact with an annular face of said fine grinding ring, the contacting annular face of each rough grinding ring being formed with both lateral and radial channels therein through which coolant may flow to flush ground material etc. from the abrading surfaces of said grinding rings.

9. A coolant circulating grinding tool for combined rough and fine grinding, comprising multiple grinding

5

rings of differing grit grain size mounted on a common axis with their annular faces in contact, the annular face of each coarser grinding ring which is in contact with an annular face of a finer grinding ring being provided

with both lateral and radial channels through which coolant may flow to scavenge ground material and loosened grit from the abrading surfaces of said grinding rings.
